UTENSIL SCRAPER

Christopher J. Halpin and Christine E. Halpin, both of 2632 Wyndale Road, Toledo, Ohio 43613, and
Eleanor K. Frisch, 3105 Navarre Ave., Oregon, Ohio
43616

Filed Sept. 20, 1971, Ser. No. 182,282

Term of patent 14 years

Int. Cl. D7—06

U.S. Cl. D7—184

FIG. 1

FIG. 2

FIG. 3

FIG. 4

FIG. 5

FIG. 1 is a top plan view of a utensil scraper showing our new design;

FIG. 2 is a side elevational view thereof, the side opposite being substantially the same;

FIG. 3 is a bottom plan view thereof;

FIG. 4 is an end elevational view on an enlarged scale as seen from the right of FIG. 1; and

FIG. 5 is an end elevational view on an enlarged scale as seen from the left of FIG. 1.

We claim:

The ornamental design for a utensil scraper, substantially as shown and described.
